DESIGN FOR A HAIR CURLER COMB

Francis James Coakley, London, England

Application May 21, 1941, Serial No. 101,048
In Great Britain April 1, 1940

Term of patent 7 years

To all whom it may concern:

Be it known that I, Francis James Coakley, a subject of the King of England, residing at London, in the Kingdom of England, have invented a new, original, and ornamental Design for a Hair Curler Comb, of which the following is a specification, reference being had to the accompanying drawing, forming part thereof.

Fig. 2 is a right side elevational view thereof;
Fig. 3 is a left side elevational view thereof.

The characterizing features of my design reside in the hair curler comb disclosed having tapered flat tail-end and a curved front end as shown.

I claim:

The ornamental design for a hair curler comb, as shown and described.

FRANCIS JAMES COAKLEY.
